DESIGN FOR A TOY DOG

Hattie E. Kelly, Mineral Wells, Tex.

Application November 7, 1938, Serial No. 80,909

Term of patent 7 years

To all whom it may concern:

Be it known that I, Hattie E. Kelly, a citizen of the United States of America, residing at Mineral Wells, in the county of Palo Pinto and State of Texas, have invented a new, original, and ornamental Design for a Toy Dog, of which the following is a specification, reference being had to the accompanying drawing, forming part thereof.

The figure is a perspective view of a toy dog, showing my new design.

What I claim is:

The ornamental design for a toy dog, substantially as shown.

HATTIE E. KELLY.
